GAS TORCH LIGHTER

Oscar V. Malmquist, Minneapolis, Minn.

Application September 3, 1943, Serial No. 501,060

4 Claims. (Cl. 67—6.1)

My present invention relates to improved methods of and apparatus for lighting gas-burning torches such as are employed in the welding and brazing arts, and has among its important objectives the provision of improved means and methods whereby such torches may be more easily and quickly ignited than by previously employed methods and apparatus.

As is well known, gas-burning torches of the kind employed in the welding and brazing arts, for example, must be frequently lighted and relighted during the course of a day's work, and close observations indicate clearly that much actual production time is lost by workers in these fields through time consumed in the lighting and relighting of their torches when previous apparatus and methods of ignition are employed. I find that one of the most commonly accepted devices for igniting such torches is in the nature of hand-held and hand-operated sparkers of the type wherein a flint is moved over sharp steel edges to produce sparks of hot metal in the presence of gas emitted from the torch. These so-called sparkers or sparking lighters have hitherto been held in one of the operator's hands during the lighting operation, while the torch was held in the other hand; and, of course, this procedure requires the temporary release by the operator of any work piece which he may have been holding with one hand.

Specific objects of the invention are, therefore, the provision of improved method and apparatus whereby the welder may quickly and easily produce ignition sparks in the presence of gas emitted from his torch and thereby ignite the torch gas, all by the use of the hand holding the torch. To this end, the invention provides a novel sparking type of lighter that is secured to a fixed support, such as a floor or work bench in a convenient location with respect to the operator's work, and is designed and arranged to be manipulated by engagement of the torch itself; the invention also providing a novel method comprising the manipulation of such a lighter by direct engagement with the movable element of the lighter and movements imparted thereto through the medium of the torch.

The above and other important objects and advantages of the invention will be made clear in the following specification, claims, and appended drawing.

In the accompanying drawing, like characters indicate like parts throughout the several views.

Referring to the drawing:

Fig. 1 is a perspective view of the preferred

embodiment of a lighter made in accordance with the invention and further indicating, by dotted lines, the preferred method of operating the lighter;

Fig. 2 is a longitudinal sectional view taken on the line 2—2 of Fig. 1;

Fig. 3 is a transverse sectional view taken on the line 3—3 of Fig. 1;

Fig. 4 is a transverse sectional view taken on the line 4—4 of Fig. 1, but showing the torch in full lines; and

Fig. 5 is a fragmentary sectional view taken on the line 5—5 of Fig. 3 and looking downwardly with respect to Fig. 3.

The preferred embodiment of the lighter illustrated comprises a flat sheet metal base element 6 having an integrally formed upturned guard flange 7, a roughened steel element 8 in the nature of a file toothed on its upper surface, a flint 9 for cooperation with the file 8, and a spring flint holder 10. The base element 6 is shown as being anchored to a fixed base of support, such as a work bench 11, through the medium of nails, screws, or the like 12. The guard flange 7 extends completely around one segmental end of the base element 6 and is extended for a considerable distance along one side thereof. The flint 9 is directly mounted in a head 13 applied to the free end of the flint carrying spring 10. At its other end, spring flint carrier 10 is bent downwardly at 14, transversely at 15, and upwardly at 16 to provide a U-shaped anchoring portion which transversely embraces one end portion of the base element 6; the base portion 6 and extended side of the guard flange 7 being inwardly pressed to provide channels 17 and 18 for receiving anchoring portions 14 and 15 of the spring flint carrier. The file 8 is seated on and extends across the upwardly pressed base portion forming channel 17, and is provided with a notch 19 at one end to receive the in-pressed portion forming channel 18, and is notched at its other end to receive the upturned end 16 of the spring flint holder 10.

Initially, the upturned end 16 of the spring 10 forms a right angle with respect to the transversely extending portion 15 thereof, but after application of the file the upturned end 16 is further bent inwardly to lock the file in position.

The file is thus placed under longitudinal squeezing pressure which, due to the close fitting of its notched ends, prevents lateral tipping action thereof, as well as vertical displacement.

The flint 9 rests upon the toothed surface of the file 8 and the spring flint holder which is

coiled intermediate its ends normally maintains the flint adjacent one extreme end of the file; and, in fact, normally maintains the head 13 against the upstanding portion 16, which latter serves as a stop to prevent the spring 10 from carrying the flint beyond that end of the file. Now, it will be clear that movement of the flint over the file, against the action of the spring 10, will produce sparks of hot metal capable of igniting gas from the welder's torch.

The operative end of a conventional welder's torch is indicated as an entirety by 20, by dotted lines in Fig. 1, and by full lines in Fig. 4; and this torch may be assumed to be connected to a conventional source of gas supply not shown, and which will be emitted from the free end of the tip of the torch. Now, by reference particularly to Figs. 1, 3, and 4, it will be seen that the spring flint holder is bent adjacent the head 13 to provide a notch 21 for receiving the free end portion of the tip of the welding torch 20.

The improved method of lighting the torch comprises engaging the free end of the torch tip with the notched portion 21 of the flint holder, which portion 21 is closely adjacent the flint 9 and file 8; and then by movement of the torch tip, moving the flint 9 over the file 8 against the action of the spring 10, while gas is being emitted from the end of the torch. Actuation of the lighter in this manner requires the use of only the operator's hand already engaged in holding the torch; and, of course, the operation may be repeated as many times as is necessary to ignite the torch. Due to the location of the notch 21 and consequent location of the gas-emitting end of the torch immediately adjacent the flint 9 and file 8, gas from the torch will be concentrated about the area from which sparks are emitted, and ignition will take place very rapidly. Even in locations where there is considerable draft which would tend to carry the gas away from the sparking area, the guard flange 7 will offer sufficient protection to insure rapid ignition by concentrating or pocketing the gas in the critical area.

From the drawing and above description thereof, it will be seen that that part of the spring flint carrier 10 lying above and in parallel relation to the base element 6 comprises connected opposite legs 10a and 10b, and integrally formed coupling coil portion 10c, vertical leg-action portions 14 and 16, and a transverse horizontal portion or leg 15. It will be further seen that the notched ends of the file element 8 receive the vertical portions or legs 14 and 16 of the spring flint holder, and are tightly clamped therebetween. While in the preferred embodiment of the invention the flange 7 is provided for the purpose of pocketing or concentrating gases in the critical area, it will be clear that this flange could be omitted without defeating the novel manner of anchoring the spring flint holder between the legs 14 and 16 of the flint holder, and in which case the leg 14 would engage one notched end of the file 8 directly rather than through the medium of the interposed notched portion of the guard flange 7. It will be understood, however, that the walls of the channel in the guard flange do aid materially in anchoring the spring flint holder against accidental movements, particularly in a direction upwardly of the base.

Herein, the term "flint" is used in a broad and

liberal sense to include any element which will function as a flint to produce sparks when brought into frictional engagement with another element, and the term "file" is likewise used in a broad and liberal sense to include any device which will cooperate with a flint-acting element to produce such sparks as are required for gas ignition.

What I claim is:

10. 1. A lighter of the kind described comprising a substantially flat base element adapted to be secured to a suitable base of support, a lighter file extending transversely across said base, a flint carrying spring comprising connected opposite legs overlying the base, a flint carried by the end of one leg of said spring flint carrier and overlying the file, the other leg of the said spring flint carrier being formed to provide downwardly, transversely, and upwardly extending portions, the said transversely extending portion extending under said base element directly beneath the file, and said downwardly and upwardly extending portions engaging opposite edges of the base portion and exerting squeezing pressure on the opposite ends of the file, whereby to anchor the spring flint holder and file to the base.
15. 2. The structure defined in claim 1, in which the opposite ends of the file are notched to receive the said downwardly and upwardly extending portions of the spring flint holder, and in further combination with a gas-confining guard flange upstanding from the edge of the base and extending between one notched end of the file and the downwardly extending portion of the spring flint holder, said flange being formed with an in-pressed channel receiving the downwardly extended portion of the spring flint holder and which in-pressed channel is directly received in the adjacent notched end of the file.
20. 3. A lighter of the kind described comprising a substantially flat elongated base element adapted to be secured to a suitable base of support, a lighter file extending transversely across and anchored to said base adjacent one end of the elongated base element, a flint carrying spring overlying said base element and comprising connected opposite legs, a flint carried by one end of one leg of said spring flint carrier and disposed over the said file, the other leg of the spring flint carrier being anchored to said base element, and a gas-confining guard flange upstanding from the margin of the base element and extending around the end portion thereof adjacent the lighter file.
25. 4. A lighter of the type described comprising a substantially flat base adapted to be secured to a suitable relatively stationary support, an abrasive surface extending transversely across and anchored to said base adjacent one end thereof, a swinging carrier for a spark emitting element said carrier being anchored to the base and having a free end overhanging the abrasive surface, a spark emitting element carried by said free end portion of the swinging carrier for rubbing movement on the abrasive, said swinging carrier being provided adjacent its free end with a torch tip receiving and guiding recess, and gas confining flange means on the lighter assembly for restraining gas emitted by the torch tip to the region of the spark emitting element.

OSCAR V. MALMQUIST.
